[57] CLAIM

The ornamental design for an electronic storage cabinet

and lighted sign assembly for an automatic teller machine, as shown and described.

DESCRIPTION

FIG. 1 is a front view of a electronic storage cabinet and lighted sign assembly for an automatic teller machine showing our new design;

FIG. 2 is a right side elevational view;

FIG. 3 is a top plan view;

FIG. 4 is a bottom view;

FIG. 5 is a front, top and left side perspective view;

FIG. 6 is a rear view thereof;

FIG. 7 is a front elevational view of a second embodiment of FIGS. 1-6;

FIG. 8 is a right side elevational view of FIG. 7;

FIG. 9 is a top plan view of FIG. 7;

FIG. 10 is a front, top left side perspective of FIG. 7;

FIG. 11 is a rear view of FIG. 7;

FIG. 12 is a front elevational view of a third embodiment of FIGS. 1-6;

FIG. 13 is a right side elevational view of FIG. 12; and, FIG. 14 is a front, top left side perspective view of FIG. 12 thereof.

The showing of FIGS. 7, 8, 10 and 11 have been broken away for ease of illustration.
